UNITED STATES PATENT OFFICE.

LOUIE T. CARL AND ALBERT S. CARL, OF WINONA, MISSISSIPPI.

RADIO RECEIVING SET.

Application filed January 21, 1924. Serial No. 687,541.

To all whom it may concern:

Be it known that we, LOUIE T. CARL and ALBERT S. CARL, citizens of the United States, residing at Winona, in the county of Montgomery and State of Mississippi, have invented certain new and useful Improvements in Radio Receiving Sets, of which the following is a specification.

This invention relates to improvements in 10 radio receiving sets and apparatus, and particularly to the assembly and mounting of the several elements of the set.

An object of the invention is to provide 15 a radio receiving set having the receiving elements mounted in compact relation so that substantially direct connection may be made between the several elements for placing them in proper circuit relation for eliminating bus wires and other connecting 20 wires in common use and thereby eliminating local interference noise affecting the efficient reception of radio waves.

Another object of the invention is to assemble the several parts of the receiving 25 apparatus for providing substantially direct contact between the terminals of the elements and forming the terminal carrying parts of the structure with slots between the adjacent terminals so that air gaps are provided 30 between the different parts of the circuit of the receiving apparatus to increase the insulating qualities in the set and to prevent dust, dampness and other foreign matter which accumulate on the supporting 35 structure for the several receiving elements, and causes leakage in the circuit.

A further object of the invention is to 40 provide a condenser structure including a bracket mounted on one side of the slot in the panel for supporting a plurality of stationary condenser plates in spaced relation for cooperation with movable condenser plates mounted on the shaft adapted for rotation in a bracket carried by the panel 45 and secured thereto at the opposite side of the slot in said panel, with operating means on the outside of the panel having reduction gears interposed between the operating means in the rotary shaft for moving the movable condenser element considerably 50 slower than the operation of the operating element in order to obtain a more efficient adjustment of the relation between the condenser elements.

55 The invention also comprehends other objects and improvements in the details of

construction which are directed toward eliminating undesirable noise and induction in the set, and for providing a structure in which the circuit connections are made with 60 a minimum amount of wire and which results in a compact assembly of the parts so that they may be mounted in a small space, as well as to provide for a finer adjustment of the movable element including the circuit 65 to obtain better reception of messages.

The accompanying drawings illustrate the preferred form of the invention, in which

Figure 1 is an end elevation of the assembly, the housing therefor being shown in section. 70

Figure 2 is a plan view of the panel and the assembly carried thereby, a portion of the housing being shown in section. 75

Figure 3 is a vertical transverse section thru a portion of the panel, showing the manner of mounting the condenser element and a stationary tuning coil.

Figure 4 is a sectional view, taken on the 80 line 5—5 of Figure 1 showing a rear view of a portion of the panel assembly.

Figure 5 is a rear elevation of the panel assembly with the tuning coils removed 85 from their mountings.

Figure 6 is a side elevation of a portion of the coil and block shown in Fig. 1.

Figure 7 is a detail view of the upper parallel portion of the frame carried by the auxiliary panel, showing the main contact 90 terminals mounted thereon and the slot formed therein to provide air gaps between these terminals and portions of the feet of the lamp holding frame secured to said parallel portion. 95

Figure 8 is a detail sectional view thru one of the lamp contact receiving sockets shown in Fig. 7.

1 indicates the main panel of the receiving set which forms the front of the 100 open ended casing 2, providing a housing for the receiving instruments and mountings for the set to protect the same against dust and other foreign matter. An auxiliary panel 3 is mounted in the rear of the main panel in spaced relation therewith through the use of spacing elements 4, the said auxiliary panel being of relatively small size and carrying a member 5 composed of upper and lower spaced parallel 105 portions 6 and 7, respectively, connected with and extending rearwardly from the 110

auxiliary panel and a connecting portion 8 between the rear ends of the parallel portion for holding them in spaced relation and cooperating therewith and with the 5 auxiliary panel to provide means for mounting the receiving instrument relative to the panels.

The auxiliary panel 3 is formed with the horizontally extending slot 9 in the central 10 portion thereof between the upper and lower frame portions 6 and 7 to provide an air gap between the bracket members 10 and 11 mounted on the panel. The bracket member 10 is formed with a sleeve 15 extension 12 which receives a rod 13 on which is mounted a plurality of stationary condenser plates 14 in spaced relation with one another. The outer end of the rod 13 extends through an opening 15 in the 20 connecting portion 8 of the frame 5 to provide an air gap around the ends of the rod with respect to the frame, one part of the separable contact members 16 being mounted on the end of said rod, while the 25 other part thereof is carried by a connection block 17 which mounts the stationary tuning coil 18 through the contact member 16 and another contact member 19 formed of separable sections, one of which is carried by the block 17 and the other being mounted in the connecting portion 8 of the frame, whereby one terminal of the coil 18 is directly connected with the condenser and is removably mounted relative to the 30 auxiliary panel through the separable contact members 16 and 19. The connection block 17 is provided with a slot 20 extending transversely of the block to provide an air gap between the separable contact members 16 and 19 for the purpose of increasing the resistance between the circuits in which these members are located for preventing leaks and local interference.

The stationary condenser plates 14 are 45 formed of substantially semi-circular plates provided with openings 21 located adjacent the straight edge of the plate and to one side of the center, each plate being provided with a recess 22 at the other side 50 of the center for purposes to be presently described.

The bracket 11 forms a bearing for rotatably mounting a shaft 23 which is adapted to receive on the inwardly projecting 55 end thereof a plurality of spaced semi-circular movable condenser plates 24 positioned between the plates 14 and mounted on the shaft 23 to one side of the central portion thereof and formed with recesses 60 to the other side of the central portion in a similar manner to the construction of the plates 14 above described. This is to provide for a cooperation between these 65 plates in the rotation of the shaft 23, so that the opposed area of the plates in in-

termeshed relation for each adjustment of the movable plates between the stationary plates will be substantially the same, the recesses permitting the movement of the movable plate around the rod mounting the 70 stationary plate so that the entire surfaces of each plate may be opposed to one another in intermeshed relation, the recesses in the edges of the stationary plate receiving the shaft 23 which mounts the movable 75 plate as clearly shown in Fig. 4 of the drawings in order that the entire surfaces of both sets of plates may be opposed to one another.

A separable contact member 25 having 80 relatively rotatable parts has one of the parts mounted on the ends of the shaft 23 and the cooperating parts mounted in the connecting part 8 of the frame 5, so that a connection between a desired stationary 85 instrument and the movable condenser plate may be effected. A suitable form of vernier dial may be mounted on the forward end of the shaft 23, for adjusting the movable condenser plate with micro-metric fineness to secure good tuning.

The upper parallel portion of the frame 5 is formed adjacent the rear edge thereof with cross slots 44 between which are mounted resilient sockets 45 for receiving the contacts of the usual bulb 46 used in the receiving circuit, each of the contacts having an air gap between them by reason of the slots 44. Each of the sockets 45 is composed of a plate 46 having an inclined extension 47 to provide means for receiving an attachment screw for connecting circuit wires thereto, and a plurality of resilient fingers 48 which receive and make contact with the depending contact points on the bulb 46, a depending extension 49 extending through the part 6 of the frame, and receiving nuts 50 adapted for securing the sockets to the frame. A skeleton holder is also provided for the lamp 46 and includes a ring 51 provided with a plurality of lateral extensions 52 formed at their lower ends into securing feet 53 adapted to be secured to the upper portion 6 of the frame in any suitable manner, the ring 51 receiving the base of the lamp 46 when the contacts are in engagement with the resilient socket and providing a firm mounting for the bulb. A rheostat 54 is mounted on the panel 1 above the upper end of the auxiliary panel 3 and is provided with the usual adjusting handle 55 for operating the movable contacts of the rheostat to adjust the currents of the filament of the lamp 46, the rheostat being interposed in the circuit connected with the lamp in the usual manner.

Movable tuning coil supports are mounted at each side of and adjacent the frame member 5 and include upper bearing 130

brackets 56 and cooperating roller brackets 57 pivotally mounting bracket members 58 through the medium of the pivot pins 59, the rear ends of the brackets being provided with plates 60 extending laterally from the bracket members toward the frame member 5. The ends of these plates adjacent the frame member are provided with pairs of contact members 61, each being formed of cooperating sections, one section of each contact member being mounted on the plate while the other section of each contact member is mounted on blocks 62 carrying movable coils 63, the terminals of which are connected with the contacts. The blocks 62 are similar in construction with the block 17 and are provided with slots providing an air gap between the contact members as indicated by dotted lines in Figure 2. Each of the plates 60 is slotted as at 64 between the mountings of the contact members to provide an air gap for adding resistance between the contacts to prevent leakage in the circuit to the coils. The bracket members 58 are rotatable on their pivots and carry worm gears 65 at their upper ends with which mesh the worm 66 mounted on the shafts 67 which are rotatable in the bearings of said brackets 58 and extend through openings in the auxiliary panel and the main panel for receiving operating handles 68 and dials 69 on the outer end thereof in front of the panel to provide manual means of moving the coils 63 relative to one another and the coil 18.

The panel 1 is provided with the usual sight opening 70 for viewing the filaments of the lamp 46.

In the arrangement of the parts above described, it will be noted that very little wire is needed to connect the several instruments of the receiving set, which may be arranged in a circuit for receiving radio messages in any desirable manner for producing the desirable results, several forms of circuits using the apparatus above described being well known in the art.

It will be noted from the above description that a feature of the invention resides in providing air gaps between all adjacent contact members and mountings of different circuit connections in order to increase the resistance between the different parts of the circuit, for preventing dampness and dust which collect on the mounting structure, from permitting leakage in the circuit and consequent noise and reduction of efficiency in operation of the set.

Another feature of the invention resides in the construction of the auxiliary panel with the frame carried thereby, the condenser element mounted on the panel within the portions of the frame, stationary coil mountings provided directly in

connection with the condenser elements, and the lamp mounting carried by the frame in close proximity to the condenser and coils so that short wires may be used for connecting these parts in the circuit in order to prevent internal inductance in the set.

What is claimed is:

1. A tuning unit mounting including a panel having a horizontally extending slot 75 in the central portion, a pair of bracket members mounted on the rear side of the panel at opposite sides of the slotted portion and having tubular extensions thereon, a rod mounted in and extending from the tubular extension of the upper bracket, said rod being adapted to receive a plurality of stationary condenser plates for mounting in spaced relation thereon, the end of the rod being adapted to receive a circuit connection, a shaft rotatable in the sleeve extension and bracket on the lower side of the slot, said shaft being adapted to mount a plurality of movable condenser plates in spaced relation between the stationary 90 plates, a contact member mounted on the inner end of said shaft having relatively rotatable sections, one of the sections being free from the shaft, and an operating disc on the outer end of the shaft in front of the 95 panel.

2. A tuning unit mounting including an auxiliary panel adapted to be mounted in the rear of a main panel, said auxiliary panel having a slot formed in the central 100 portion, a pair of bracket members mounted on the auxiliary panel at opposite sides of said slot having tubular extensions thereon, a rod removably mounted in one of the bracket members, a plurality of stationary 105 condenser plates mounted in spaced relation on said rod, a shaft rotatable in the other bracket member and extending through the auxiliary panel, and a plurality of movable condenser plates mounted in spaced relation 110 on the shaft and extending between the stationary plates.

3. A radio tuning unit, including a panel having a slot formed in the central portion thereof, a pair of bracket members mounted on the rear side of the panel at opposite sides of the slotted portion and formed with tubular extensions, a rod mounted in and extending from the tubular extension on the upper bracket, a plurality of stationary 115 condenser plates of semi-circular form having bulged portions at one side of the center of the straight edge thereof provided with openings for receiving said rod and provided with recessed portions on the opposite sides of the center thereof, said plates being mounted in spaced superposed relation on said rod, a shaft rotatable in the sleeve extension and bracket on the lower side of the slot, said shaft being received by the recesses 120 125 130

in the stationary condenser plates and spaced from said plates, a plurality of movable condenser plates of semi-circular form having bulge portions at one side of the center of the straight edge thereof provided with openings for receiving the shaft and formed with recesses at the opposite side of the center on the straight edge thereof for receiving the rod mounting the stationary condenser plate, said movable condenser plates being mounted in spaced relation on said shaft for cooperation and movement between the stationary condenser plates whereby the mounting of the plates at one side of the center thereof on the rod and shaft respectively and the provision of recesses at the other side of the center of the plate provide means for permitting the movement of the plates into superposed relation for obtaining a maximum capacity in the circuit, and operating means on the front face of the panel for permitting the manual ad-

justment of the movable condenser plates relative to the stationary plates.

4. A tuning unit mounting comprising an auxiliary panel adapted for mounting on the panel of a radio set, a frame member mounted on said auxiliary panel and projecting laterally therefrom, a pair of bracket members mounted in adjacent relation on the auxiliary panel, said panel being formed with a slot between the bracket members, a condenser structure mounted on said bracket, terminal elements mounted on said frame and connected with the condenser structure, said terminal elements being further adapted to removably support an inductance coil on the frame, and connect said coil in circuit with the condenser.

In testimony whereof we affix our signatures.
